UNITED STATES PATENT OFFICE.

ALBERT P. SOLLENDER, OF PORTLAND, OREGON.

VEHICLE-LIFT.

1,263,954.

Specification of Letters Patent. Patented Apr. 23, 1918.

Application filed March 29, 1917. Serial No. 158,397.

To all whom it may concern:

Be it known that I, ALBERT P. SOLLENDER, a citizen of the United States, residing at Portland, in the county of Multnomah and 5 State of Oregon, have invented a new and useful Vehicle-Lift, of which the following is a specification.

This invention relates to vehicle lifts adapted especially for raising and lowering 10 motor vehicles by means of a demountable and portable device to and from a suitable height to allow work and repairing to be conveniently carried on without the use of a pit with its numerous disadvantages.

15 The further object of this invention is to provide an absolutely sure and safe device for raising and lowering the vehicle which will be operated by the weight of the vehicle.

It will be readily seen that this device 20 has many advantages over a pit in that it is cleaner, more accessible to light, more convenient for work, does not permanently occupy space and may be used where a pit could not be constructed, and may be moved 25 from place to place.

In the drawings, Figure 1 is a side elevation of the vehicle lift showing the trackway in a position to receive the vehicle. Fig. 2 is a plan view of the lift.

30 The lift consists of two identical units, parallel spaced and held at the proper distance by means of spacing rods. It may be constructed in various sizes and the construction or means of holding parts together 35 modified from that shown in the drawings without departing from the principle of my invention.

The reference numeral 1 designates the base of each of these units on which is 40 mounted a horse 2 fastened to the base but detachable. Across this horse is centrally hinged a tilting trackway 3 as shown, with flanges to guide the wheels, of sufficient length to support the vehicle and to reach 45 the floor and form an incline of suitable pitch. The trackway may be detached by removing the pin from the hinge. On the base 1 near each end is mounted a vertically disposed cylinder 4. In each of said cylinders is a piston 5 provided with a connecting rod 6 extending upward to the trackway, said rods being attached to the piston and trackway by means of a pivot joint easily detachable from the trackway. The

two cylinders are connected by a pipe 7 55 provided with a valve 8. The chamber of each cylinder below the piston is filled with a sustaining fluid such as oil or water. The pipe connected into the bottom of the chamber allows the fluid to flow from one cylinder to the other. The bases and trackways of the two units are connected and held at the proper distance by spacing rods 9 and 10 respectively, the rods being easily detachable. Approximate to each end of the trackways is a hinged leg 11 to give support when the trackways are in a horizontal position. 60

65 The operation of my device is substantially as follows: The vehicle to be repaired is driven up the inclined trackway 3 when 70 the trackway is in position shown in Fig. 1, or if the vehicle is without power it is pulled up by means of a block and tackle or other leverage attached to the ends of the trackways or to a point outside of the device. 75 When the greater weight of the vehicle passes the center and the valve 8 is opened the fluid will be forced from the front cylinder, which then bears the greater weight, 80 into the rear cylinder. The trackways and vehicle will thus gradually descend to a horizontal position where it may be sustained by closing the valve or by allowing it to rest on the leg. The vehicle may be shifted, 85 when it is desired to descend, thus throwing the weight to whichever end it is desired to lower. By then opening the valve and folding the leg it will slowly lower itself for dismounting. By closing the valve the vehicle may be held at any angle. Blocks 90 or other device will be used to prevent rolling of the wheels while the trackway is inclined.

95 Having thus described my invention what I claim and desire to secure by Letters Patent is:

1. In a vehicle lift the combination of two units parallel spaced, each including a base supporting a horse upon which is hinged a tilting trackway, a cylinder and piston at 100 each side of the pivot of said trackway, and a connecting duct between said cylinders, whereby the fluid contained in the cylinders may pass from one cylinder to the other as the trackway rocks, and means for controlling the flow of the liquid. 105

2. In a vehicle lift the combination of two identical units parallel spaced, each consist-

ing of a base supporting a horse upon which is centrally hinged a tilting trackway with cylinders attached to the base approximate to its ends fitted with pistons to which are 5 pivotally secured connecting rods the upper ends of which are pivotally secured to the trackways, the said cylinders being con-

nected by a pipe fitted with a valve through which a supporting fluid contained in the chamber below the pistons may flow from one cylinder to the other in moving the trackways to and from a horizontal position. 10

ALBERT P. SOLLENDER.
